UNITED STATES PATENT OFFICE.

LEON J. CAMPBELL, OF CHICAGO, ILLINOIS.

HIGH-SPEED DRILL.

1,048,035.

Specification of Letters Patent.

Patented Dec. 24, 1912.

Application filed October 16, 1911. Serial No. 654,897.

To all whom it may concern:

Be it known that I, LEON J. CAMPBELL, a citizen of the United States, and a resident of Chicago, in the county of Cook and State 5 of Illinois, have invented a new and useful Improvement in High Speed Drills, of which the following is a complete specification.

The main objects of this invention are to 10 provide a high speed drill having a detachable bit; to provide a high speed drill in which the bit or cutting portion is relatively short as compared with the shank and is formed of a much harder metal than the 15 shank; to provide a high speed drill in which the shank is adapted to have various sizes of bits attached thereto, so that a number of sizes of holes may be drilled with one shank by simply changing the bits; to provide 20 improved means for attaching the bit to the shank; and to provide an improved high speed drill in which the drill may be quickly and easily detached from or attached to the shank.

25 The invention consists of the matters hereinafter described in the specification and more fully pointed out in the appended claims.

In the drawings: Figure 1 is a fragmentary side elevation of a high speed drill embodied in this invention. Fig. 2 is an end elevation of the cutting end of the drill. Fig. 3 is a side elevation of the joint end of the shank. Fig. 4 is a view of the joint end 35 of the shank taken at right angles to that shown in Fig. 3. Fig. 5 is an end elevation of the joint end of the shank. Fig. 6 is a top plan view of the bit shown in Fig. 1. Fig. 7 is a side elevation of the bit shown in Fig. 1. Fig. 8 is a side elevation of the bit taken at right angles to the view shown in Fig. 7. Figs. 9 and 10 are side elevations of the locking pin or key for the bit. Fig. 11 is a fragmentary side elevation of a modified 45 form of the drill. Fig. 12 is a side elevation of the joint end of the shank shown in Fig. 11. Fig. 13 is a side elevation of the bit shown in Fig. 11. Fig. 14 is a bottom plan view of the bit shown in Fig. 11.

50 Referring first to the construction shown in Figs. 1 to 10, inclusive, the shank 1 of the drill is shown as a twist drill and is formed of relatively soft, tough steel. The lower or joint end 2 of the shank is provided with a 55 central longitudinally directed diametrically disposed slot 3, which divides the end into

jaws 4 and 5. The outer face 6 of each jaw is in alinement with the side of the shank and the bearing or contact face 7 of each jaw is beveled or inclined in a plane at right angles to the plane of the slot 3 so as to give endwise tapered form to the jaw, while the inner faces 8 of the jaws, or those formed by the slot 3, are parallel with the central longitudinal axis of the shank. The jaws 4 and 5 have their beveled faces 7 oppositely inclined and laterally offset from each other both at the bases and outer ends of the jaws so that the lines indicating the beveled faces, as seen in the side view of the shank, Fig. 4, cross or intersect each other and present a V-shaped opening 9 between the outer ends of the said jaws. Each of the jaws 4 and 5 is provided with a transverse groove or key seat 10 in its inner face, or that adjacent the slot 3, and the outer end of each jaw is abrupt or squared. The bit 11 is also twisted, but is flat and of less torsion than the shank, and may be of a width or diameter equal to or greater than the diameter of the 50 shank 1. The joint end of the bit is provided with oppositely beveled jaws 12 and 13, which have their front faces 14 beveled complementally with the faces 7 of the shank and are adapted to seat on said faces 55 7 when the bit is in place. At the lower end of each face 14 is an abrupt or squared shoulder 15 having a cross sectional shape or area equal to that of the abutting end of the jaws 4 and 5. When the bit is in operative position the shoulder does not quite contact with the end of the jaw of the shank. Said shoulders are formed by the upper ends of downwardly and laterally extending ribs 16 which terminate in a point at the corners 90 17 of the bit. The inner faces 18 of said ribs are curved to carry the shaving or chips into the flutes 19 of the shank. The inner edges of the jaws 12 and 13 are connected by a web 20 adapted to enter the groove 3 of 100 the shank when the bit is in place, and an aperture or key seat 21 extends through the inner edges of the jaws and through the web. When the bit is placed on the shank the key seat 21 partially registers with the key seats 105 10 and a drift pin or key 22 is adapted to extend through said seats, and when forced into place tends to draw the bit onto the shank and rigidly lock it in place.

In the construction shown in Figs. 11 to 110 14, inclusive, the bit 23 has the same degree of torsion or twist as has the shank 24. The

bit and shank are also provided with overlapping jaws 25 and 26 respectively, and the jaws 25 of the bit are connected at their inner edges by a web 27 which projects beyond the ends of the jaws and enters a slot 28 in the shank. The jaws 25 and 26 on each side of the drill are provided with key seats 29 formed in the inclined or beveled faces thereof (see Fig. 11), one half 10 of each seat being in each of the jaws 25 and 26, and keys 30 are adapted to be secured in said seats to hold the bit firmly in place.

The operation is as follows: A bit of the same or greater diameter than that of the shank is placed on the shank and the drift pin or key is inserted in the key seats, and when pounded or forced into said seats it acts to draw the jaws of the bit firmly up 20 into the jaws of the shank. When it is desired to replace the bit with one of a different size it is only necessary to knock out the pin and the bit may be removed from the shank.

25 The jaws of the shank and bit are so arranged that, when in operation, the jaws of the shank push against the jaws of the bit, thereby avoiding any tendency to open the joint.

30 Obviously many details of the construction shown may be varied or omitted without departing from the scope of the claims.

I claim:

1. A drill, comprising two members, a shank and a removable bit therefor, each member having endwise extending jaws overlapping those of the other member, the jaws of each member being located at opposite sides of a plane passing through the central longitudinal axis of the drill and having their bearing or contact faces oppositely inclined to give endwise tapered form to said jaws, and fastening means for locking said members together, acting to draw 40 the jaws of the bit and shank longitudinally toward each other.

2. A drill, comprising two members, a shank and a removable bit therefor, each

member having a pair of endwise extending jaws overlapping those of the other member, 50 the jaws of each member being located at opposite sides of a plane passing through the central longitudinal axis of the drill and having their bearing or contact faces inclined or beveled to give endwise tapered 55 form to said jaws, and fastening means for locking said members together embracing endwise facing, transverse surfaces on the said members, and a locking member engaging said surfaces and acting to draw the 60 jaws of the bit and shank longitudinally toward each other.

3. A drill, comprising two members, a shank and a removable bit therefor, each member having a pair of endwise extending 65 jaws overlapping those of the other member, the jaws of each member being located at opposite sides of a plane passing through the central longitudinal axis of the drill and having their bearing or contact faces inclined or beveled to give endwise tapered 70 form to said jaws, and fastening means for locking said members together, consisting of oppositely disposed transverse key seats in the jaws of the bit and shank, and a key 75 adapted to engage said seats.

4. A drill, comprising two members, a shank and a removable bit therefor, each member having a pair of endwise extending jaws overlapping those of the other member, 80 the jaws of each member being located at opposite sides of a plane passing through the central longitudinal axis of the drill and having their bearing or contact faces inclined or beveled, to give endwise tapered 85 form to said jaws, said members having transverse key seats formed in the inclined or beveled surfaces of its jaws, and a key adapted to engage said key seats.

In testimony whereof I have hereunto 90 subscribed my name in the presence of two witnesses.

LEON J. CAMPBELL.
